SHUTTLE MOTION FOR LOOMS

Journey F. Timberlake, Charlottesville, Va., assignor of twelve and one-half per cent to Robert L. Wright, Richmond, Va., twelve and one-half per cent to H. Newell Goodwin, one and one-half per cent to H. Earl Thomas, and one and one-half per cent to Percy E. Thomas, all of Charlottesville, Va.

Application December 31, 1935, Serial No. 57,043

17 Claims. (Cl. 139—133)

The present invention relates to new and useful improvements in shuttle motions for looms and particularly to the novel structure and combination of parts whereby the same may be carried out.

In my Patent No. 2,002,194, issued May 21, 1935, I have disclosed a particular type of structure used in effecting a positive and easily controlled shuttle motion. In that structure weighted pins were disposed so as to be displaceable upwardly against a cam surface on the shuttle so as to reciprocate the shuttle through the shed. While my patented arrangement possesses many fine advantages, I have found that that particular type of structure has the disadvantage of producing considerable noise. Also, the weight of the movable pins requires the expenditure of a considerable amount of power. The present invention obviates these disadvantages.

I am aware that other types of lay frames have been used and patented in which movable pins strike a cam surface to actuate a shuttle; also, that geared shuttles have been moved through a shed on a rack; and finally, that shuttles have been forced between warp threads by means of an endless belt. With respect to the first of these types of structures, it may well be said that the tremendous number of moving parts makes the same costly and erratic. Moreover, it has been found that the cam surfaces must be greased to prevent great inherent friction. The grease invariably finds its way to, and soils, the cloth.

In using the gear and rack type of shuttle track, it is necessary to run the warp threads over the rack. The gear teeth and rack teeth press or crush the warp threads in such a way as to make them rough and to impair their tensile strength.

The belt type of shuttle track is impractical. Belts, regardless of the material from which they are made, are subject to changes in length. Constant adjustment is required. Furthermore, the warp threads which lay upon the belt are not restrained at that point against sidewise movement. Entanglements result.

The present invention has for an object the correction of all these defects. Simplicity of operation and construction have been attained. The number of moving parts has been reduced, and no greasing of the track is necessary. Another object of the invention is the provision of a track which is constantly self-adjusted.

A further object of the invention is the production of a shuttle track which has incorporated therein means for holding the warp threads

against lateral movement without subjecting the threads to chafing wear.

All of the lay frames not using cam pins known to me are so constructed that it is possible to use only a single shed in the process of weaving. This is because a continuous track for the shuttle traverses the loom.

As a further object this invention proposes to combine with the lay a novel type of comb, a part of which acts as the track. This object of the invention contemplates the use of this novel comb in combination with two shuttles moving simultaneously, and further, the use of two simultaneously moving shuttles for laying two weft threads in a double shed.

While the particular type of shuttle movement may be used on substantially all types of looms and in combination with various types of shed forming means, in the appended drawings the novel shuttle track is shown on a particular type of loom, parts only of which will be described with reference to the drawings. In such description allusion will be made to the various figures throughout which like reference numerals indicate like parts and in which:

Fig. 1 is a front elevational view of a loom with the breast beam broken away to show the lay in elevation and

Fig. 2 is a side elevation of the same showing the comb used in single shed weaving, and

Fig. 3 is a rear elevational view of a fragment of the lay and shuttle structure, and

Fig. 4 is a section along line 4—4 of Fig. 3, and

Fig. 5 is a top plan view of the portion shown in Fig. 3 showing by arrows the direction of movement of the lay, and

Fig. 6 is a side elevational view of the lay and comb used in double shed weaving, and

Fig. 7 is a rear elevational view of the same along line 7—7 of Fig. 6, and

Figs. 8 and 9 are plan views of the two types of comb elements.

Referring particularly to Fig. 1, the lay 2 is shown as supported movably on the loom side frames 4 and 6.

The lay consists of an upper cross beam 8 and a lower cross beam 10 held spaced apart and made into a rigid substantially rectangular frame by uprights 12 and 14. The cross beams 8 and 10 are greater in length than the distance across the loom so that the lay may extend beyond the side frame of the loom. Motors 16 and 18 are mounted on the under side of the cross beam 10 and are suitably connected to drum reels 20 and 55

22 which in turn are supported at the ends of the lay. It will be understood that cables upon these drums act indirectly to move the shuttle across the lay.

5 All of the structure with which the novel shuttle motion is effected is contained within the lay frame 2. As shown in Figs. 1, 3 and 4, attached upon the upper surface of the lower cross beam 10 is an angle iron 46 one of the sides of which 10 is disposed in a vertical plane. Approximately one-third of the distance between the lower beam and the top beam are the angle irons 48 and 50. These angle irons extend horizontally across the lay frame 2 with their ends attached to the up- 15 rights 12 and 14. These angle irons are spaced apart so that a suitable carriage (to be described later) may run between them and be guided thereby. Also extending horizontally between the uprights 12 and 14, and having its ends attached thereto, is a spiral spring 52. This spring 20 52 is preferably of any suitable spring steel wire and is attached to the uprights so as to be under tension. A second and like spring 54 also is attached at its ends to the uprights under tension just below the lower surface of the upper cross beam 8.

A cam-forming carriage 56 runs in the space between the angle iron 46 and the spring 52, while a shuttle carriage runs between spring 52 and the spring 54. The carriage 56 may be constructed in any suitable way but preferably consists of two inverted T-shaped frames 58 and 60 and three grooved wheels 62, 64 and 66. The wheels 62 and 64 are rotatably arranged on suitable axles 30 which are situated at suitable points in the cap portion of the T-shaped frames but spaced inwardly from the ends of the frame so that cables 65 and 67 may be attached to holes near the ends of the frames. The third wheel 66 is supported on an axle which extends between the stem portions of the T-shaped frames in a plane above the other two axles such that at least a portion of the wheel 66 will be disposed above the normal line of the spring 52. The spring member 52 is disposed in the groove of this third wheel 66 and as the carriage moves the wheel 66 will continually raise the spring member 52 to cause the contacted portion of the spring member to form a cam-like surface.

50 The shuttle carriage which runs between the springs 52 and 54, serving as tracks, may be of any well known form. A carriage of the type shown in my previous patent would suffice. However, there is here shown a carriage 68 which is 55 slightly more compact since it consists of two substantially U-shaped frames 70 and 72, the stems 74 and 76 of which are on an angle and diverge upwardly away from each other. Supported between the frames on suitable axles are 60 grooved wheels 78 and 79. The two wheels 78 are supported on axles at the lower outside corners of the U-shaped frame and the two upper wheels 79 are supported on axles which extend between the frames near the upper ends of the stems 74 and 76.

65 While the shuttle cop 80 is shown as arranged at one end of the shuttle carriage, it is understood that it may be arranged in any other suitable manner upon the frame 70 and 72. For instance, the cop may be mounted within the frame with the spindle parallel to the frame or vertical thereto. The shuttle carriage 68 is mounted above the cam-forming carriage 56 with the wheel 66 of the latter situated between the two lower 75 wheels of the former.

With reference to Fig. 1, when it is desired to move the shuttle from the position in which it is shown toward the right end of the lay, the motor 18 will be energized by any suitable means to drive the drum reel 22. The cable 65 will be wound upon the drum reel and the carriage 56 5 pulled through the shed. As the carriage 56 is pulled through the shed a cam surface is formed by the raised portion of the spring 52. By the action of this cam surface upon one of 10 the lower wheels of the shuttle, the shuttle is positively driven through the shed and a weft thread is left therein.

A further novel and unexpected result is achieved when the shuttle is moved across the 15 lay. While the cam surface as at 82 is formed on the spiral spring, the spring track 52 moves slightly about its horizontal axis. Ordinarily the lower warp threads of the shed will be situated between the spirals of the spring as shown in Fig. 4. However, it is well known that changing the shed in 20 substantially all types of looms often results in that the warp threads are displaced laterally. In most types of looms this displacement of the warp threads would constitute a great disadvantage 25 since it would be necessary to place the warp threads in their proper positions by hand to keep them from being sheared off upon passage of the shuttle. The tendency of the spring track 52 to turn about its longitudinal axis makes such hand 30 work unnecessary in my novel loom.

I have found that this turning motion of the track precedes the passage of the carriage through the shed by about six inches. Any warp threads which may have been displaced in changing the shed are automatically replaced because the portion of the spring upon which they are resting is turned out from under them. The warp threads automatically drop down into the interstices between the various wrappings of the 40 spring. In that position they are protected from any frictional wear or crushing because the wheels 66 and 78 are held spaced apart by the spring upon which they run. It will be understood that the upper warp threads which form 45 the shed are situated between the various wrappings of the upper spring 54. These warp threads are thus protected from the wear which might otherwise be caused by the upper wheels of the shuttle carriage.

50 The lay, shuttle tracks, motors and reels are all mounted as a unit in such a way that they may be moved toward and away from the cloth being formed. As shown in Figs. 1 and 2, substantially tubular tracks 24 and 26 are supported upon, and 55 in spaced relation to, the inner faces of the loom frames 4 and 6 by suitable brackets such as 28 (see Fig. 2). Wheels 30 having a grooved surface of such cross section as to fit snugly on the tracks 24 and 26 are swung from the bottom of beam 18 60 and rest upon the tracks.

It is necessary to guide and support the upper portion of the lay during the operation of beating up the weft in order to keep the lay from toppling over. In Fig. 2 I have shown a U-shaped steel 65 upright 32, but it is understood that two such uprights may be used, each of which is attached by the legs of the U to the top and bottom cross beams 8 and 10 of the lay, such that the perpendicular portion of the upright is spaced away 70 from the rear face of the lay. One of such uprights is attached to the lay 2 at each side in the manner described above in substantially the same plane as the loom frames 4 and 6. However, the uprights are of a width greater than the thickness 75

of the said frames so that the rod 34 on the outside of the frame may be pivotally attached thereto by the pivot bracket 36, while the guide rod 38 on the inside of the loom frame may be attached thereto by means of the socket 40. The intermediate portions of the guide rod are slidably supported in a horizontal, substantially cylindrical socket 42 on the inner side of the loom frame. While the rod 38 and the guide socket 42 have been shown on the inside of the loom frame, they may be supported on the outer side but at a higher level so that they will clear the drive wheel 44.

In combination with this novel shuttle movement, this invention contemplates the use of a novel comb made up of a plurality of flat steel reeds shown in detail in Figs. 8 and 9. The former of these is to be used in single shed weaving, while that shown in Fig. 9 will be described in connection with my double shuttle motion used in double shed weaving of filled and other fabrics.

The individual comb elements 84 are long, flat, rectangular bands of steel which may be die-cut from a suitable gauge of steel sheet or other material. At the same time, as the elements are cut from the sheet of steel, they may be provided with a perforation at each end.

As shown in Fig. 8, brackets 86 and 88 are attached to the top and bottom cross beams of the lay. The brackets are spaced apart and the distance between them will be controlled by the width of the cloth to be weaved. These brackets extend outwardly from the rear face of the lay frame only for such a distance as to allow for clearance of the shuttle carriages and weft thread in their passage through the shed. Long bolts 90 and 92 extend through, and are supported by, the brackets 86 and 88. The bolts in turn hold and support the individual comb elements 84 which are arranged in a vertical position and with the bolts extending through the perforations. Suitable spacers, preferably steel washers or the like, are arranged between the comb elements so that the warp threads may move freely up and down between the elements when the shed is changed.

The operation of the lay in beating up the weft will be clearly understood by those versed in the art. Briefly, the movement is as follows: After the shuttle has made a passage through the shed leaving behind a weft thread, the shuttle remains stationary at the end of the lay frame as shown in Fig. 1. Drive wheel 44 which is driven by any suitable prime mover revolves in the direction shown by the arrow in Fig. 2, and rod 34, (of which, there may be two, one on each side of the loom) will force the lay frame toward the cloth beam upon tracks 24 and 26. The guide rods 38 serve to make the movement smooth and straight, while they prevent the lay frame from toppling over. After a short forward movement the front edges of the comb elements 84 engage the weft thread and the continued movement will carry the weft thread toward the cloth. The lay is then returned, a new shed is formed, and the operation begins again.

The double shuttle arrangement shown in Fig. 6 and Fig. 7, is a further development of my invention. In this embodiment two shuttles and two cam-forming carriages are used. There are 5 horizontal guide tracks extending between the uprights. The outermost guide tracks consist of angle irons 46' and 46'' one of which is attached to the upper surface of the lower lay beam 8. Spaced inwardly from these guide tracks, two helical spring tracks 52' and 52'' of the type pre-

viously described, are stretched. Each of these spring guide tracks is flanked on each side by horizontal angle irons which prevent lateral movement of the carriages. That is to say, these angle irons prevent the carriages from falling over sidewise. The fifth track is composed of a plurality of substantially circular projections 96 on the comb elements which are arranged across the lay and slightly spaced away from each other. The upper peripheries of the projections form a track for an inverted shuttle and the lower peripheries form a track for the lower shuttle.

The five tracks limit 4 paths of movement 98, 100, 102 and 104 all in the same vertical plane. The lowermost path of movement 98 and the uppermost path of movement 104 are each limited on their outer sides by the single angle iron guide rail and on their inner sides by the horizontal springs. In the lowermost path of movement a cam-forming carriage 58' is placed with the two grooved wheels lowermost and the single wheel uppermost. Thus the two grooved wheels ride on the angle iron and the single wheel is in contact with the lower spring 52'. The top path of movement is occupied by another but inverted cam-forming carriage 58'' as clearly shown.

The two inner paths of movement are divided at their center by the track formed by the projections 96 on the comb elements. They are separated from the uppermost and lowermost paths of movement by the springs tracks. Two shuttle carriages are mounted for movement in these inner paths of movement. The upper of the two shuttle carriages is inverted.

Each of the shuttle carriages has two grooved wheels on the spring tracks. The remaining two wheels ride upon and are guided by the peripheries of the projections 96 on the comb elements. It will be understood that the shuttle wheels riding on the spring tracks straddle the cam-forming wheel on the cam carriage, and that the latter is drawn through the shed as described above in connection with the first form of the invention. It will be further understood by those skilled in the art that the two shuttles may be moved through the shed in the same direction simultaneously or in sequence, or that they may be moved in opposite directions.

Referring now to Fig. 9, the elements 94 are die cut from a steel sheet of a gauge which is sufficiently heavy to insure substantial rigidity. The elements are perforated at the ends so that bolts may be passed therethrough. Preferably the comb element may be described as a depressed equilateral triangle with a small circle at its apex. That is, the rear edge of the element is a straight line and may be described as the base of the triangle. The sides of the element are bowed inwardly and are thus curved from the apex toward the upper and lower ends of the comb so that clearance is afforded for passage of the shuttles. A circular projecting portion 96 integral with the comb element is arranged at the apex. The distance from the center of this circular projecting portion to the rear edge is such that the former will lie in the same vertical plane as the spring tracks when the comb is assembled on the lay.

The three levels of warp threads which are to be used are shown in Fig. 7. The upper and lower threads are oblique and form a shed in a well known manner, while the third thread extends in a horizontal line from the cloth beam

through the lay, between the comb elements, to the harness which controls the said thread. A single passage of the shuttles through the shed will lay therein two weft threads or a single weft thread and a filler thread as desired. The upper of these two will fall downwardly until it rests upon the horizontal warp threads. The lower of the two will be supported at some point on the lower oblique warp threads.

10 A slight change has been made in the path of movement which the lay follows in beating up these weft threads. The cylindrical tracks 24 and 26 and the guide rods 38 have been described heretofore as being horizontally supported on 15 the loom frame. When using the double shuttle movement I have found it advantageous to arrange the said lay tracks and the guide frames on the loom frame at an angle oblique to the floor, the end towards the finished cloth being 20 higher. As the lay moves forward on the inclined track to beat up the weft, the lay frame and the comb elements connected thereto will be raised relative to the level of the upper weft thread. The 25 projection 96 will thus pass above the upper weft thread and both weft threads will be packed into the finished cloth by the lower portion of the comb edge.

While I have shown and described the preferred forms of my invention, it will be understood that 30 I do not limit myself thereby.

What I claim is:

1. A shuttle motion for looms comprising, a comb, a pair of shuttles, a track projecting from 35 said comb between said shuttles, a pair of flexible tracks at the sides of said shuttles opposite said first track and means for displacing said flexible tracks intermediately of each shuttle progressively in the direction of their longitudinal axes whereby the shuttles are moved progressively.

40 2. A shuttle motion for looms comprising, a comb, a pair of shuttles, a track provided with interstices for warp threads projecting from said comb between said shuttles, a pair of flexible tracks at the sides of said shuttles and means for 45 displacing said flexible tracks intermediately of each shuttle progressively in the direction of their longitudinal axes whereby the shuttles are moved progressively.

3. A shuttle motion for looms comprising a 50 comb, a pair of shuttles, a track projecting from the comb between the shuttles, a pair of flexible tracks at the sides of the shuttles opposite the first track, said first track being provided with interstices and said flexible tracks being provided 55 with gaps for warp threads and means for displacing said flexible tracks intermediately of each shuttle progressively in the direction of their longitudinal axes whereby the shuttles move progressively.

60 4. A shuttle motion for looms comprising, a comb, a pair of shuttles track projecting from said comb between said shuttles, a pair of flexible tracks at the sides of said shuttles opposite said first track and means for simultaneously 65 placing said flexible tracks intermediately of said shuttle progressively in the direction of the longitudinal axis of said track and causing partial rotation of said flexible members progressively in front of said shuttles whereby said shuttles are 70 moved and warp threads are positioned progressively.

5. A shuttle motion for looms comprising a 75 shuttle carriage, flexible means provided with gaps for guiding all of the threads of the lower set of warp threads at all times during movement

of the shuttle carriage, and rigid means for supporting said flexible means against downward movement, and means for causing successive portions of said flexible means to exert a cam action on said shuttle carriage to actuate the same.

6. A shuttle motion for looms comprising a shuttle carriage, a coil spring in the interstices of which all of the threads of a set of warp threads are disposed during movement of the shuttle carriage, rigid means for supporting said coil spring against downward movement, and means for causing successive portions of said flexible means to exert a cam action on said shuttle carriage to actuate the same, said flexible means also constituting a guide for the shuttle carriage.

7. A shuttle motion for looms comprising a shuttle carriage, flexible means provided with gaps for continuously guiding warp threads during movement of the shuttle carriage, a support for said flexible means, said support comprising a pair of spaced members running the length of said flexible means, the space between the members being less than the cross sectional diameter of the flexible means, and means for causing successive portions of said flexible means to exert a cam action on said shuttle carriage to actuate the same.

8. A shuttle motion for looms comprising a shuttle carriage, flexible means constituting a guide for the shuttle carriage and provided with gaps for continuously guiding a set of warp threads during movement of the shuttle carriage, a support for said flexible means, said support comprising means running substantially the length of said flexible means and supporting the latter only on two parallel lines spaced from the vertical center of said flexible means and so as to leave the upper portion of said flexible means free to guide the shuttle carriage and the set of warp threads, and means for causing successive portions of said flexible means to exert a cam action on said shuttle carriage to actuate the same.

9. A shuttle motion for looms comprising, a shuttle carriage, flexible means provided with gaps for continuously guiding a set of warp threads during movement of the shuttle carriage, means for supporting said flexible means with a portion throughout its length above the plane of the set of warp threads, and means for causing successive portions of said flexible means to exert a cam action on said shuttle carriage to actuate the same.

10. A shuttle motion for looms comprising, a shuttle carriage, flexible means provided with gaps for continuously guiding warp threads during movement of the shuttle carriage, means for supporting said flexible means with a portion throughout its length permanently above the plane of the set of warp threads, and means for causing successive portions of said flexible means to exert a cam action on said shuttle carriage to actuate the same, said flexible means forming one track for said shuttle carriage.

11. A shuttle motion for looms comprising, a shuttle carriage, a cam-forming carriage, and flexible means between said shuttle carriage and said cam-forming carriage for continuously holding a set of warp threads in position during movement of the shuttle carriage and for transmitting motion of the cam carriage to the shuttle carriage, and means for supporting said flexible means with a portion throughout its length permanently above the plane of the set of warp threads.

12. A shuttle motion for looms comprising,

flexible means provided with gaps each of which is adapted to receive a thread of a set of warp threads, at least one shuttle carriage adapted to be guided in its passage by said flexible means, means for causing successive portions of said flexible means to exert a cam action on said shuttle carriage to actuate the same, and means for supporting said flexible means in a position in which all of the threads of a set of warp threads are disposed in gaps in said flexible means, whereby each warp thread of the set is maintained in proper position during the entire period of the passage of the shuttle carriage in one direction.

13. A shuttle motion for looms comprising, a shuttle, a flexible track above and a flexible track below the shuttle, said tracks being provided with gaps for continuously guiding warp threads during movement of the shuttle, means for displacing one of said tracks intermediately of said shuttle progressively in the direction of the longitudinal axis of said track whereby the shuttle is moved progressively, and means for supporting said flexible tracks against outward movement in a plane containing the longitudinal axes of said tracks.

14. A shuttle motion for looms comprising, at least one shuttle carriage, flexible means provided with gaps for continuously guiding warp threads during movement of a shuttle carriage, means for supporting said flexible means with a portion throughout its length permanently extending above the plane of the warp threads, and means for simultaneously causing successive portions of said flexible means to exert a cam action on said shuttle carriage and to cause partial rotation of said flexible means in front of said shuttle whereby said shuttle is actuated and warp threads are kept in proper position.

15. A shuttle motion for looms comprising, a

shuttle carriage, flexible means provided with gaps for continuously guiding the warp threads during movement of the shuttle carriage, rigid means for supporting said flexible means, means for causing successive portions of said flexible means to exert a cam action on said shuttle carriage to actuate the same, a heddle for the warp threads, and means for moving the heddle a sufficient distance to bring the warp threads into the gaps of said flexible means when the latter is in its normal position.

16. A shuttle motion for looms comprising a shuttle carriage, flexible means provided with gaps for continuously guiding a set of warp threads during movement of the shuttle carriage, said flexible means being arranged substantially on the same level as the set of warp threads to be guided, means for supporting said flexible means with a portion throughout its length permanently extending above the plane of said set of warp threads so as to constitute a guide for said shuttle carriage, and means for causing successive portions of said flexible means to exert a cam action on said shuttle carriage to actuate the same.

17. A shuttle motion for looms comprising a shuttle carriage, flexible means provided with gaps for continuously guiding a set of warp threads during movement of the shuttle carriage, said flexible means extending substantially across the loom in the direction of the shuttle carriage path, means for supporting said flexible means with at least a portion throughout its length permanently extending above one of the planes of the set of warp threads, and means for causing successive portions of said flexible means to exert a cam action on said shuttle carriage to actuate the same.
